UNITED STATES PATENT OFFICE.

WILLIAM H. PRITCHETT, OF THE UNITED STATES MARINE CORPS.

SHOWER-BATH FIXTURE.

1,241,765.

Specification of Letters Patent. Patented Oct. 2, 1917.

Application filed July 17, 1917. Serial No. 181,132.

To all whom it may concern:

Be it known that I, WILLIAM H. PRITCHETT, of the United States Marine Corps, a citizen of the United States, stationed at Sanchez, 5 in the Dominican Republic, have invented certain new and useful Improvements in Shower-Bath Fixtures; and I do hereby declare the following to be a full, clear, and exact description of the invention, such as 10 will enable others skilled in the art to which it appertains to make and use the same.

My present invention relates to improvements in shower bath fixtures adapted for use in bath houses, private bath rooms, or 15 the like, where there is fixed pipe for supplying water already located; and it consists in certain novel features, as will be hereinafter described and claimed.

Reference is had to the accompanying 20 drawings, in which;

Figure 1 shows the attachment connected to the city water main;

Fig. 2 shows a central vertical section through the shower bath fixture, part of the 25 stem being shown in elevation;

Fig. 3 shows a section along the line 3—3 of Fig. 2, and looking in the direction of the arrows;

Fig. 4 shows a central vertical section of 30 the cup, which forms a valve seat for the stem; and

Fig. 5 is a detail showing the stem in elevation.

1 represents the water main controlled by 35 any suitable valve 2, from which project one or more water pipes 3, which preferably project downward as at 4, and to which downward projections the cap 5 is connected as by the screw threads 6. This cap is also provided with internal screw threads 7, to engage corresponding threads on the cup 8, which is provided with an annular recess 9 connected by the ports 10 formed in the wall 11 to the valve chamber 12, which is preferably tapered, as shown in Figs. 2 and 4, to receive the plug or stem 13, which plug or stem has one or more ports 14 adapted to register with the ports 10 when the stem is turned in the proper direction.

For convenience in assembly, the top of 50 the stem 15 is made angular, as shown. The bottom of the stem is provided with screw threads 16 to engage corresponding screw threads 17 in the neck 18 of the shower-head 19, whose bottom is provided with a plate 20, perforated as at 21.

In assembling the parts, the plug or stem 13 is inserted in the valve chamber of the cup 8, and by holding on to the head 15 with a wrench, the shower-head 19 is screwed 60 tight on the stem, the cup is then screwed into the cap 5, and the cap is screwed into the pipe 4. Water may be kept permanently supplied to the pipe 4 by the main valve 2; and when the bather desires to turn on the 65 shower, he reaches up and turns the shower-head 19, and with it the stem 13, until the ports 14 register with the ports 10. It will be seen that the stem may be turned so as to either partly or wholly open the ports 14, 70 and thus the supply of water to the shower-head may be regulated at will by simply turning the shower-head.

The shower-head is preferably located at 75 any convenient height somewhere above the head of the bather, but within easy reach of his arms.

For use in a large bath house, a single main 1 may be connected to any number of showers, and the whole main may be controlled by a single valve 2, while each individual shower may be controlled by turning the shower-head, and thus opening and closing the ports 14. By this arrangement the pressure of the water on the stem tends to 80 keep the stem closed, and the conical shape of the stem and its chamber will tend to 85 cause the valves to wear uniformly, thus automatically securing a tight joint.

While I have shown two ports 10 in the 90 wall 11 of the cup 8, and two ports 14 in the hollow stem 13, it will be obvious that a single port in each may be used, or more than two ports may be used, if desired.

Having thus described my invention, what 95 I claim and desire to secure by Letters Patent of the United States is:

1. In a shower bath apparatus, the combination with a water main and a water pipe connected thereto, of a hollow cap 100 connected to said pipe, a cup secured to said cap and provided with a tapered central chamber and an annular recess therein, with one or more ports connecting said annular recess with said central chamber, a tapered 105 hollow plug rotatably mounted in said central chamber, and provided with one or more ports adapted to register with the ports in said cup, and a shower-head attached to said plug and adapted to rotate 110 said stem when turning pressure is applied thereto, substantially as described.

2. In a shower bath apparatus, the combination with a water main and a water pipe connected thereto, of a hollow cap screwed to said pipe, a cup screwed to said cap and provided with a tapered central chamber and an annular recess therein, with one or more ports connecting said annular recess with said central chamber, a tapered hollow plug rotatably mounted in said central chamber, and provided with one or more ports adapted to register with the ports in said cup, said plug projecting beyond said cup and being provided with screw threads on its projecting portion, and a shower head screwed tight to said plug and adapted to rotate said stem when turning pressure is applied thereto, substantially as described.
3. A shower bath attachment adapted to be connected to a fixed water pipe comprising a hollow cap connected to said pipe, a cup secured to said cap and provided with a tapered central chamber and an annular recess therein, with one or more ports connecting said annular recess with said central chamber, a tapered hollow plug rotatably

mounted in said central chamber, and provided with one or more ports adapted to register with the ports in said cup, and a shower-head attached to said plug and adapted to rotate said stem when turning pressure is applied thereto, substantially as described.

4. A shower bath attachment adapted to be connected to a fixed water pipe comprising a hollow cap screwed to said pipe, a cup screwed to said cap, and provided with a tapered central chamber and an annular recess therein, with one or more ports connecting said annular recess with said central chamber, a tapered hollow plug rotatably mounted in said central chamber, and provided with one or more ports adapted to register with the ports in said cup, said plug projecting beyond said cup and being provided with screw threads on its projecting portion, and a shower-head screwed tight to said plug and adapted to rotate said stem when turning pressure is applied thereto, substantially as described.

In testimony whereof, I affix my signature.
WILLIAM H. PRITCHETT.
